CHILD'S PLAYHOUSE

Ursel Gabriel, Dayton, Ohio, assignor to Waltz Manufacturing Company, Dayton, Ohio, a corporation of Ohio

Filed May 8, 1961, Ser. No. 65,053

Term of patent 14 years

(Cl. D34—15)

FIG. 1 is a perspective view of my design for a child's playhouse, as seen from a corner thereof; and

FIG. 2 is a perspective view of my new design, as seen from an adjacent corner to the corner from which FIG. 1 is viewed.

I claim:

The ornamental design for a child's playhouse, as shown.
